UNITED STATES PATENT OFFICE.

ISRAEL CHARET, OF NEW YORK, N. Y.

SCALE.

1,078,417.

Specification of Letters Patent. Patented Nov. 11, 1913.

Application filed August 15, 1912. Serial No. 715,185.

To all whom it may concern:

Be it known that I, ISRAEL CHARET, a subject of the Czar of Russia, and a resident of the city of New York, borough of Brooklyn, in the county of Kings and State of New York, have invented a new and Improved Scale, of which the following is a full, clear, and exact description.

This invention relates generally to scales, and, more particularly, it is directed to a combination of levers co-acting with the platform and suitable indicating mechanism, whereby the load on the platform may be indicated by the said mechanism.

10 The principal object of my invention is to provide a new and improved means of mounting the scale platform, the construction being characterized by the adjustability 15 of the parts, whereby the fulcrum may be varied in order to vary the effects of different loads on indicating mechanism used therewith.

More particularly, the construction comprehends an arrangement of parts adapted 25 for use with the scale head shown and described in my co-pending application, Serial No. 668,283, filed December 28, 1911.

The construction to be described and claimed comprehends a plurality of levers 30 which are termed primary and secondary levers, movably mounted in position and in co-active relation, the mounting being characterized by the use of knife edges, whereby the centers of movement of moving parts are 35 main fixed, thereby tending to greater accuracy and also to less wear and tear because the engaging surfaces are a minimum.

It is also of some importance in the art of scale-making, especially those of the so-called springless variety, that a construction be produced which may be supplied at low cost in order to meet the growing competition, such low cost, however, not being obtained at the expense of accuracy or adjustability.

Reference is to be had to the accompanying drawings, forming part of this specification, in which similar characters of reference denote corresponding parts in all the 50 views, and in which—

Figure 1 is a plan view of the platform frame showing the arrangement of the parts; Fig. 2 is a vertical sectional view on the line 2—2 of Fig. 1; Fig. 3 is a sectional view on the line 3—3 of Fig. 1; Fig. 4 is a sectional view on the line 4—4 of Fig. 1;

Fig. 5 is a sectional view on the line 5—5 of Fig. 3; Fig. 6 is a sectional view on the line 6—6 of Fig. 3; Fig. 7 is a sectional view on the line 7—7 of Fig. 6; Fig. 8 is a sectional view on the line 8—8 of Fig. 2.

In describing the particular embodiment of the invention set forth in the drawings, it is, of course, understood that such particular form is typical only of a certain preferred arrangement of parts, it being clear that various departures may be made from what is shown without avoiding the inventive idea disclosed. Such matters as those of size, shape, and form, as well as the choice of materials in making the separate parts are largely matters of skill and may be determined in any instance by a person skilled in the art.

Generally speaking, the construction involves a base 1 of any desired form and shape, preferably provided with supports 2, one end portion of the base being closed by a top 3 having an opening 4 therein, this top 3 carrying a vertically extending hollow shaft 5 within which the draft rod 6 leading to the indicating mechanism is housed. As shown in the drawings, the parts mentioned, as well as those to be subsequently described, are preferably made of channel iron, the same being used because of the adaptability of such material to bending and shaping.

That portion of the base 1 beyond the top 3 and toward the other end of the structure is left open and above this open portion is a metal frame 7, the shape of which preferably corresponds to the shape of the base, the platform 8 being mounted on this frame 7, the combined structure being in co-operative relation with the said draft rod 6 by means of the levers and mountings to be presently described.

Referring particularly to Fig. 1, it will be noted that the structure comprises what may be termed a longitudinally extending primary lever 9, movably mounted in position, and a plurality of secondary levers on opposite sides thereof, which secondary levers are shown as substantially triangular in outline, although such conformation is, of course, not arbitrary. Each secondary lever comprises the three members 10, 11, 12, suitably held together in any desirable manner, as by means of rivets or screws 13. It will be noted that the ends of the members 11, 12, engage the member 10 remote from the ends, the ends 14 of which member 10

are offset or bent and provided with other offsets 15 removed from the offsets 14 and extending in an opposite direction. It will also be noted that the members 11, 12, do not come together adjacent their ends but that the member 11 is extended for a suitable distance, as shown particularly in Fig. 4, the construction and co-operation of these extended ends being later set forth.

Referring particularly now to Figs. 5 and 6 in connection with Fig. 3, the particular manner of mounting the ends of the secondary levers in relation with the base 1 will be set forth. The inside of the base 1 is provided with a plurality of brackets 16, each bracket carrying a support 17 having a notch or recess 18 in its upper face in which a knife edge 19 carried by the end 14 of the member 10 is entered. This bearing or support 17, as indicated preferably in Fig. 7, is in the nature of a plate having recesses 20 extending inwardly from its ends, which recesses receive upstanding pins or lugs 21 carried by the said bracket 16. Thus it will be noted that while the bearing or support 17 is fixed with relation to the base 1, it is adjustably fixed in the sense that it may be moved to the best position in order to conveniently receive the knife edge 19 carried by the offset end 14 of the member 10. As shown particularly in Figs. 1 and 3, the other offset end 14 of the member 10 is mounted in a similar manner.

The second offset portions 15 of the member 10 which are adjacent the ends of this member are in pivotal relation with the structure which carries the platform 8, the arrangement being shown especially in Figs. 1, 4, and 5. Extending transversely of the frame 7 which carries the platform 8 and secured to the said frame is a beam 22, the beam having downwardly extending hangers 23 with notches 24 at the lower ends, the bottoms of the notches being provided with steel inserts 25 forming bearings for knife edges to be presently described.

Referring particularly to Fig. 5, it will be noted that the upper portion of the offset 15 is provided with an upwardly extending knife edge 26 and that resting on this knife edge is a block or bearing 27 having a recess in its face, receiving the said knife edge, this bearing or block being carried in a frame 28 substantially rectangular in shape, the lower side 29 of which extends outwardly, forming arms 29' (Fig. 3) which arms are provided with knife edges 30 engaging in the before mentioned notches 24 in the lower end of the hangers 23. It is clear from the drawings that the other offset portion 15 adjacent the other end of the member 10 is mounted in a manner similar to what has just been described. To this end, it will be noted from Fig. 1 that the frame 7 which carries the platform 8 is provided with a

plurality of beams 22 to which the said hangers 23 are secured.

It will be clear now that if any load is placed on the platform 8 and if the adjacent ends of the members 11 of the secondary levers are suitably supported, this load will be transmitted to these secondary levers, the fulcrums of which are the knife edge support 17, 19, adjacent the offset ends 14, the points of application of the load being the knife edge supports 26, 27, engaging the offsets 15, the moment due to the application of the load to the lever being transmitted to the primary lever 9 in varying amounts, depending on the load, the manner of mounting the adjacent ends of the members 11 being now set forth.

Referring particularly to Figs. 2 and 4, it will be noted that the primary lever 9 has suitable masses of material 31 adjustably secured adjacent one end, the other end of the lever being provided on its under side with a fixed knife edge 32 bearing in a suitable support 33, carried by the lower portion 34 of a frame 35, the upper end of which is provided with a knife edge 36 in engagement with the lower hooked end 37 of the said draft rod 6. Extending transversely of the lower portion of the base are fixed elements 38. Bridging these fixed elements are beams 39 provided with slots 40; on top of each of the beams 39 is a suitable support 41 having an extended base with openings therein through which bolts 42 pass, these bolts engaging in the said slot 40 and serving to fix the position of the support 41 relatively to the beam 39. The upper portion of each support 41 is provided with a bearing 43 having a notch in its upper side adapted to co-act with knife edges 43' carried by the under side of a substantially U-shaped frame 44.

Referring particularly to Fig. 8, it will be noted that extending transversely of the primary lever 9 is an adjustable element 45 having a yoke 46 extending downwardly therefrom which embraces the said lever 9, the element 45 being adjustable with respect to the lever 9 and being held in position by tightening of the set screw 47.

Referring now to Fig. 1, it will be noted that the opposite side portions of the element 45 are provided with slots 48 and that the said U-shaped frames 44 are adjustably mounted on this element 45, engaging therewith through the medium of the said slots 48, permanent relation of the parts being maintained by means of the set screws 49. This fulcrum of the primary lever 9 is adjustable; in fact, the fulcrums on opposite sides of the said lever may be independently adjusted, due to the provision of the U-shaped frames and the slotted element co-operating with these frames.

In order to transmit the load carried by

the platform to this primary lever through the medium of the said secondary levers already described, knife edge mountings, substantially of the following construction, are 5 availed of. Referring particularly to Figs. 2 and 4, it will be noted that the adjacent ends 11' of the members 11 of the secondary levers are provided with downwardly extending knife edges 50. It will also be 10 noted that the said primary lever 9 is provided with a transversely extending element 51 having a plurality of notched bearings 52 carried thereby; a plurality of substantially rectangular frames 53, the upper portions 15 54 of which constitute knife edges and the lower portions 55 of which are provided with notched bearings 56, serve to transmit the load from the secondary levers to the primary one through the engagement of the 20 knife edges 50 in the supports 56, the knife edges 54 and the bearing or support 52.

In order to permit a certain amount of relative movement of the platform with respect to the base but still not enough to 25 range the relation of the movable parts, a number of links 57 (Fig. 1) are made use of, one end of each of which is secured to the base of the scales at 58, the other end being provided with a slot 59 receiving an 30 upstanding pin 60 positioned at the outer end of an offset 61 carried by the said beam 22 secured to the platform frame.

From a description of the structure and operation set forth, it is believed that the 35 co-action of the parts will be apparent.

Any load placed on the platform will move the secondary levers through a certain angle, the movement of these levers being in turn imparted to the primary lever, movement of which is opposed because of the 40 masses of material 31 carried adjacent one end thereof, the primary lever swinging about its fulcrum and actuating the draft rod 6, whereby the weight of the material 45 on the platform is transmitted to the indicating mechanism.

It will be apparent that the movement of the end of the primary lever which actuates the draft rod will depend upon the distance 50 between the fulcrum of the said lever and the point at which the load is transferred thereto from the secondary levers. This distance may be varied at will by means of the construction shown, a most precise position 55 being obtainable by reason of the independent adjustment of parts on opposite sides of this primary lever which have been particularly described.

Having thus described my invention, I 60 claim as new, and desire to secure by Letters Patent:—

1. A scale comprising a base, a primary lever, a plurality of independently adjustable supports between the lever and the said 65 base, means whereby a draft rod may be

connected to the said lever, a plurality of secondary levers on opposite sides of the primary lever, a plurality of pivotal supporting means between the secondary levers and the base, pivotal mounting means between the secondary levers and the said primary lever and positioned between one end of the said lever and the said supporting means, a platform, and a plurality of pivotal supporting means between the platform and the said secondary levers. 70 75

2. A scale comprising a base, a primary lever, a plurality of independently adjustable knife edges between the said lever and the base, a plurality of secondary levers, 80 each secondary lever comprising a framework, a plurality of knife edges carried by each secondary lever and engaging the said base, a platform, a plurality of knife edges between the platform and each of the said 85 secondary levers, and a plurality of knife edges between the said secondary levers and the said primary lever.

3. A scale comprising a base, a primary lever pivotally carried thereby, the pivotal mounting comprising a plurality of independently adjustable knife edges, the said primary lever being provided with means whereby it may be connected to a draft rod, the said primary lever being also provided 90 with a mass of material adjustably mounted in position, the said pivotal mounting of the lever being intermediate the point of application of the draft rod and the said mass of material, a plurality of independent secondary levers, knife edges between the secondary levers and the base, and other knife edges between the secondary levers and the primary lever and engaging the primary lever between the pivotal mounting 100 105 thereof and the point of application of the said draft rod.

4. The improved means for adjustably mounting a lever in position in the base of a scales, comprising an element extending to 110 opposite sides of the lever and adjustably secured thereto, a plurality of supports carried by the base, a plurality of U-shaped frames carried by the said element, the said frames being provided with knife edges engaging the said supports, each of the supports in each of the frames carrying the knife edges being independently adjustable. 115

5. A scale comprising a base, a primary lever, adjustable knife edges for supporting the lever on the base, secondary levers, knife edges for supporting the secondary levers on the base, a platform, knife edges for supporting the platform on the said secondary levers, and knife edges between the said secondary levers and the said primary lever. 120 125

6. A scale comprising a base, a primary lever movably supported thereby, the supporting means comprising adjustable knife edges, the primary lever being adapted to be 130

connected to a draft rod, secondary levers on opposite sides of the primary lever, knife edges for supporting the secondary levers on the base, and knife edges between the secondary levers and the primary lever, whereby movement of the secondary levers is transmitted to the primary lever and thence to the draft rod.

7. A scale comprising a base, a primary lever, secondary levers associated with said primary lever, means for adjusting said primary lever in position on said base, said means comprising journal members carried by the primary lever and extending transversely thereof, said journal members being adjustably secured to the primary lever, supports adjustably secured to the base, means for supporting said secondary levers on said base, journal means between the secondary levers and the primary lever whereby a movement of the secondary levers is transmitted to the primary lever.

8. In a scale, the combination of a base, a primary lever, secondary levers, the said secondary levers being substantially trian-

gular in form, knife edge supports adjacent the corners of the secondary levers, a plurality of said knife edge supports engaging the base, the other knife edge support engaging the primary lever, a platform, and means whereby the platform may be movably associated with the said secondary levers.

9. The herein described means for adjustably mounting a lever in position in a scale, comprising an element extending transversely of the lever and movably secured thereto, supports carried by the base of the scale, and frames carried by the said element, the frames being provided with adjustable knife edges engaging the said supports.

In testimony whereof I have signed my name to this specification in the presence of two subscribing witnesses.

ISRAEL CHARET.
